Attorney.

UNITED STATES PATENT OFFICE.

JACOB HAISH, OF DE KALB, ILLINOIS.

RAILWAY-TRACK.

SPECIFICATION forming part of Letters Patent No. 404,401, dated June 4, 1889.

Application filed July 27, 1888. Serial No. 281,170. (No model.)

To all whom it may concern:

Be it known that I, JACOB HAISH, a citizen of the United States, residing at De Kalb, in the county of De Kalb and State of Illinois, 5 have invented certain new and useful Improvements in Railway-Tracks; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention has reference to certain improvements in railroad-tracks, both in the rails and in the ties for seating the same.

One object of my invention is to dispense with the ordinary lateral fish-plates, and thereby render it practicable to use a lower rail. It is well known that there is great lateral pressure outward upon the rails when in use from the lateral surging of the train thereon. Particularly is this the case at the curves in 25 the track where the outer rail is relied upon to give the train its changed direction. It is obvious that the higher the rail is the greater leverage this side motion of the train has upon the rail-fastening, as the pressure or concus- 30 sion from the flange of the car-wheel is against the inner side of the crest of the rail. Heretofore the vertical portion of the side of the rail—that is, the interval between the lateral flanges and the crest thereof—has been re- 35 quired to be of sufficient width to permit the placing of the external fish-plate at the joint of the rail, and yet have the wheels carried at such a height above the same that the radial flange on the car-wheels would be carried a sufficient height above said plates and the heads of the bolts which hold the same as not to come in contact therewith. In my invention by dispensing with these outside fish- 40 plates there is no reason why the crest of the rail may not be lowered to an altitude just sufficient to permit said flange on the car-wheels to be carried such distance above the lateral flange of the rail as to clear said rail-flange or any obstruction resting thereon.

50 Another advantage in my form of rail con-

sists in the fact that I give the rail a central support and also two lateral supports, the latter being directly under the sides of the crest of the rail, whereby the usual battering down of the edge of the crest of the rail is avoided. 55

In combination with my improved rail I use an iron tie provided with lugs adapted to project over the base-flanges of the rails and hold said rails in position without the use of spikes. Old and disused rails of the ordinary 60 formation may be utilized for such ties by being inverted and having the engaging-lugs formed from the lateral flanges of such old rails, and in the drawings I have shown such old form of rails adapted to be used as a tie; 65 but iron ties can be made expressly for this purpose.

In the drawings, Figure 1 is a partial perspective of the end of the rail in position upon the tie. Fig. 2 is a cross-section of the track, 70 including the rail and tie. Fig. 3 is a plan of the same, exhibiting the adjacent ends of the rails in position on the tie. Fig. 4 is a longitudinal section of the rail and cross-section of the ties. Fig. 5 is a view of the bottom of 75 the rails at their point of junction, exhibiting the corrugated bars or fish-plates resting in the vertical recesses formed in the base of the rail and extending a short distance within the end of each rail. 80

A is the rail, formed with vertical sides and the usual lateral flanges A' at the base thereof and provided with vertical longitudinal recesses B B, formed in the under side of said rail. The rails A are further provided with 85 the diagonally-formed ends C. The ends C of each rail are parallel with each other, so that in forming the junction of the rails the extreme ends of each will project past that of the other and form the diagonal junction 90 exhibited in Fig. 3. This junction may be formed as loosely as the ordinary transverse joint for the purpose of affording room for expansion, or the junction in my rail may be made closer than is usual with the transverse 95 joint, and expansion in my rails may be provided for by permitting the ends of the rails to slip slightly past each other. The advantage of this diagonal junction, as before stated, consists in making the rail substantially con- 100

tinuous, so that the tread of the passing wheel shall be supported upon the second rail before leaving the previous rail.

D D are corrugated short bars placed, respectively, edgewise in the recesses B B in the rails A and projected a short distance within the ends of said rails A for the purpose of assisting the tie to hold the ends of said rails against lateral displacement. The upper edges of the bars D are provided with transverse notches E, which enter and are held in corresponding transverse corrugations F, formed in the upper end of the recesses B in rails A. This prevents the bars D from casually slipping endwise entirely within one rail and compels said bars to remain projected within the ends of both adjacent rails, thereby breaking the joint between the latter. The bars D are corrugated laterally in order to permit a slight lateral displacement of the rails A at their junction should the excessive expansion require a slight slipping, as aforesaid, of the end of one rail past that of another.

G is a metallic tie depressed or bent downward more or less at its longitudinal center and provided upon its upper surface with engaging-lugs H, three of which are adapted to slightly extend over and engage, respectively, the contiguous external lateral flanges A' of the rail A. One of the outer lugs H upon each of the ties G, other than the end ties, has merely a vertical face as distinguished from the projecting lip of the other, in order to permit the placing of the intermediate ties after the rails are in position upon the end ties and to permit the removal and substitution of ties after the track is in position.

It will be observed that but one of the inner lugs H and but one of the outer lugs H are formed on the same side of the tie G, and each pair of opposing lugs H stand diagonally in parallel lines in reference to rail A. At the junction of the rails A lugs H engage the rails A near the extremity of the latter, thereby holding the lap of the rails A in position; also, the effect of placing the two opposing lugs diagonally at the opposite sides or edges of the ties G is to render the interval between said opposing lugs greater when the tie is placed in position diagonal with said rails, with the opposing lugs H in line perpendicular to said rails, and less when said tie is placed perpendicular to said rails. It results, therefore, from this construction that when the tie is placed under the rails, so diagonal therewith that each pair of opposing lugs are directly opposite each other transversely of said rails, the interval between the open ends of said lugs H is sufficiently great to permit the passage of the flanges A' of the rail A. When the lugs H, with the tie in its diagonal position, have been passed above the flange A', so that the rails A rest upon the tie G proper, the latter can be turned in position at right angles to the rails A, the flanges A' pass-

ing within the lugs H. To assist in this process of placing the intermediate ties, the outer lug upon one of the ties G is formed with the vertical inner face, as aforesaid, so that the operator can more readily guide the three remaining overhanging lugs into position on the flanges A' as the tie is being brought round perpendicular to the rails. As the pressure upon the rails A is about universally outward, the fact that the vertical lug H has no downward grip upon the flange A' is of little importance. The intermediate ties G can be placed alternately with their vertical lug on the outside of the different rails A, so that the grip of the engaging end lug H will be afforded upon the outside of each of said rails at each alternate tie.

The central portion of the tie G is given a downward depression J, so as to afford means of embedding said central portion with the ordinary filling material, and also to afford downwardly-extending angles K K at the ends of depression J, which, being embedded in the earth, serve to prevent any end movement of the ties G or lateral displacement of the rails A.

If desired, the ties G at the ends of the rails A may be provided with downwardly-extending ends L, as shown in Fig. 2, to further assist in holding said ties from lateral and other movement, said ends being also inserted in the ground. This mode of forming the tie G and holding the rail, together with the insertion of the bars D, make it feasible to dispense with the usual external lateral fish-plates, and therefore makes it practicable to use a much lower rail A.

The advantages of the double parallel recesses B in the rail A are that there is thereby afforded a central vertical support M, constituting the wall between said recesses and directly under the center of the rail A. The substitution of metallic ties for those of wood adds incalculably to the longevity of the ties, and inasmuch as in the form of ties shown it is feasible to use the worn-out rails such ties could be afforded largely in the first instance at a proportionately small expense.

What I claim as my invention, and desire to secure by Letters Patent of the United States, is—

1. The combination of the rail A, provided with recesses B B, and corrugations F, and bars D, provided with notches E, substantially as shown, and for the purpose described.

2. The combination of the tie G, provided with lugs H, formed in diagonal parallel lines thereon, and the rail A, provided with diagonally-formed ends C, substantially as shown, and for the purpose described.

3. The combination of the tie G, provided with lugs H, and rails A, provided with flanges A', and diagonally-formed ends C, substantially as shown, and for the purpose described.

4. The combination of the tie G, provided with lugs H, and central depression J, rails

A, provided with recesses B, and central supporting-wall M, and flanges A', and the bars D, substantially as shown, and for the purpose described.

5 5. The combination of the tie G, provided with central depression J, and lugs H, the rails A, provided with diagonal ends C, wall M, and recesses B, provided with corrugations F therein, and the bars D, provided with

notches E therein, substantially as shown, and for the purpose described.

In testimony whereof I affix my signature in presence of two witnesses.

JACOB HAISH.
